UNITED STATES PATENT OFFICE.

WM. HARVEY, OF ALBANY, NEW YORK.

JOINT FOR T-RAILS.

Specification of Letters Patent No. 21,957, dated November 2, 1858.

To all whom it may concern:

Be it known that I, WILLIAM HARVEY, of Albany, in the county of Albany and State of New York, have invented a new and Improved Joint for T-Rails; and I do hereby declare that the following is a full, clear, and exact description of the same, reference being had to the accompanying drawings, making a part of this specification, in 10 which—

Figure 1 is a side view of the ends of two rails with the joint chair and other contrivances for forming the joint. Fig. 2 is a horizontal section of the same, taken just 15 below the heads of the rails. Fig. 3 is a transverse vertical section, taken in the plane indicated by the line α , α , in Fig. 2. Fig. 4 is a transverse vertical section, taken in the plane indicated by the line y , y , in 20 Fig. 2.

Similar letters of reference indicate like parts in all the figures.

To enable others to make and use my invention, I will proceed to describe its construction and operation.

A, A, are the rails; B, is the chair; C, D, are the side plates which may be of cast iron, and are of the length of the chair, which may be of the usual length. The plate C, 30 which is applied on the outer side of the joint is intended to stand up flush with the face of the rail in order that it may form an unbroken bearing for the wheels as they pass the square extremities a , a , of the rails A, A. 35 This plate may be of such form as to fill up the recess in the side of the rail between the head and base or only to bear against the head and upon the base, leaving an open space between it and the neck of the rail. 40 The last-mentioned form is the one shown in the drawing. In either case the lower part of said plate rests partly upon the base of the rails and partly upon the outside lip b , of the chair as shown in Fig. 4. The plate 45 D, which is applied on the inner side of the joint must fit into the recess in the side of the rail, as its upper part cannot project laterally beyond the head of the rail, or it would interfere with the flanges of the 50 wheels; and its lower part, like the lower part of plate C, rests partly upon the bases of the rails and partly upon the inside lip b' , of the chair as shown in Fig. 4. This plate 55 has projecting from its inner side two strong horizontal tongues c , c , which pass through two slots d , d , cut one in each rail,

and through two slots e , e , provided in the plate C, and these tongues rest upon projections which are provided on the chair to stand up outside of the plate C, in the manner shown at i , in Figs. 3 and 4, said projections serving to support and prevent the breaking of the tongues c , c , by a heavy blow, and serving also in part to confine the plate C. The tongues c , c , are furnished 60 with vertical slots j , j , to receive keys k , k , which are driven through them and through corresponding vertical slots f , f , in the chair. These keys k , k , may also constitute spikes and be driven right through the 65 chair into the tie E, as shown in Fig. 4. The plate D is also made with a vertical slot g , g , to receive a spike h , (see Figs. 2 and 4) which is driven through it and the chair into the tie E. The chair B, is made with its 70 lips b , b' , of just the height of the flanges of the base of the rail in order that the plates C, D, may rest on both, but in this respect it 75 does not differ from many chairs in use.

The rail and chair are secured to the joint 80 tie by spikes l , l , passing through the chairs and through notches in the edges of the flanges of the base of the rail in the usual manner, and the heads of these spikes are covered by the plates C, D, in which recesses 85 r , r , are provided for them in such a manner as to prevent the possibility of the said spikes being withdrawn while the said plates are in place.

s , s , are projections on the lips b , b' , to 90 cover the ends of the recesses r , r .

The plates C, D, constructed and applied and tongued together by tongues passing through the rails and secured by the keys k , k , as described, clamp and lock the rails 95 together both vertically and laterally in the firmest possible manner so that neither can move without the other, and this method of clamping being used in connection with a plate which stands up flush with the tread 100 of the rail on the outer side of the joint makes a track which may be considered to be perfectly continuous.

Instead of the two tongues c , c , on the plate D, and two slots d , d , in the rail and e , e , in the plate C, one tongue may be used so applied as to pass through a slot made half in the extremity of each rail and a single slot in the plate C, which will serve the same purpose as the two tongues and 110 slots though in a less perfect manner.

The keys k , k , may be secured by driving

their heads laterally into recesses *m*, *m*, in the side of the plate C, as shown in red outline in Fig. 4.

The invention may be applied in combination with a chair constructed in the usual manner, that is to say without the projections *i*, *i*. I do not claim the invention of a plate which, like the plate C, stands flush with the face of the rails at the joint to serve as a bearing for the wheels in passing the joint, as I am aware that numerous different modes of applying such plates have been proposed.

Neither do I claim, generally, the use of side clamping plates. But

What I claim as my invention, and desire to secure by Letters-Patent, is:—

The arrangement and combination of the laterally-tongued side plate D, with the rails A, chair B, and side piece C, as and for the purposes herein shown and described.

WM. HARVEY.
